UNITED STATES PATENT OFFICE.

HEINRICH KARL, OF JERSEY CITY, NEW JERSEY.

AUTOMATIC REGISTER AND CONTROLLER FOR TRAINS.

Application filed May 15, 1917. Serial No. 168,904.

To all whom it may concern:

Be it known that I, HEINRICH KARL, a citizen of Germany, residing at Jersey City, in the county of Hudson and State of New Jersey, have invented new and useful Improvements in Automatic Registers and Controllers for Trains, of which the following is a specification.

Numerous attempts have been made to provide an automatic mechanism for preventing collisions between railway trains, which, however, have generally been unsuccessful because of the fact that such apparatus was so constructed that it was necessary to place more or less reliance upon the watchfulness of railway employees, and as a consequence was subject to human error.

My present invention therefore relates particularly to an improved apparatus, automatic in its operation, which will independently indicate, regulate and control the movement and operation of trains upon railroads, either wholly, or in part, independently of human assistance.

The invention also contemplates an apparatus for the above purpose which is adaptable for use in connection with various operating conditions of the railway system, and may be readily applied to any particular part of the railroad.

More particularly the invention consists in an apparatus designed for use in connection with the automatic block system of railway control, and which includes a plurality or series of switch units arranged in a circuit, which includes train control means, signaling devices, or other means located at remote points, said switch units being individually controlled by different trains located upon different railway blocks, so that the circuit will be closed only when the adjacent units in the series are automatically operated.

The above ends are attained by means of an automatic mechanism hereinafter termed a register controller, which is susceptible of arrangement so as to successfully meet the various exigencies which may arise in railway management and control, and which will automatically operate and control certain alarm, signal, switching, train stopping or other train or track devices which are arranged at different sections or located along the railroad so that a train or trains which are positioned between these automatically controlled devices, will be protected and

held at a safe distance from other trains in the front or rear, etc., and thus obviate possible disaster. Should another train from either direction attempt to approach a particular train too closely, it would be automatically signaled, switched, or stopped, through the shutting off of the propelling power, or through the application of the brakes.

While, for convenience of illustration, I have shown my invention as applied in railroad practice, it may also be practical and advantageous to use the invention for numerous other purposes, as for instance, along rivers or canals to prevent the collision of vessels. In such instance it may be necessary to modify the construction and arrangement of the parts of the apparatus in certain respects in view of the differences in the traffic conditions and requirements from those which exist upon railroads.

With the above and other objects in view, the invention consists in the improved construction, form and relative arrangement of the invention, as will be hereinafter more fully described, illustrated in the accompanying drawings, and finally incorporated in the subjoined claims.

In the drawings, wherein I have illustrated one satisfactory embodiment of the invention, and in which similar reference characters designate corresponding parts throughout the several views:

Figure 1 is a semi-diagrammatic view illustrating the use of the improved register controller in connection with a railroad, having intersections, branches, sidings, etc., and showing circuit connections with the remotely located electrically controlled devices;

Figure 2 is a side elevation of one of the switch-units of the improved register controller showing also additional means in connection therewith to be used for certain trains to automatically set a near or remote track-switch or for operating another device; a side view of an electric motor together with automatic electric switch means for the same and used for operating said track-switch are shown also as well as means to be automatically operated by trains for operating the additional means which are operatively connected with, and mounted on the register controller;

Figure 3 is a top-view of the part of the additional means of Figure 2 which is

mounted on the register controller and is serving for the operation of a track-switch or other device intended for certain trains.

Figure 4 shows in sectional side view a part of the register-controller to illustrate the three positions which the hereafter referred plate 51 is taking in the course of its operation;

Figure 5 is a plan view of a section of track showing a junction having an electric motor operated track-switch; showing also means to be automatically operated by the train and serving for closing the switch, the electric motor together with some of the mechanism for setting the switch is shown in side view in Figure 2; in Figure 5 this electric motor is situated inside the chest 55;

Figure 6 is a lug to be carried by the train and to be used for resetting the switches to closed position after all train-wheels have passed at the switch-tongues (the switch points);

Figure 7 shows the operating mechanism (in form of two chains) for the trip 63' in connection with the trip 63.

Figure 8 is a top view of this operating mechanism.

Figure 9 is a top view of the motor (55) used for operating a track-switch, showing the positions which the switch member is making during the operation of the motor and at the resetting of the track-switch.

Figure 10 is another view of the motor (55) showing also the positions of the switch member in relation with the electric contact of the motor and the lug (60) which is operating it.

Figure 11 shows a front view of the register controller and the electric circuits connected therewith; the railroad tracks are shown in plan and represent the same railroad-net as shown in Figure 1, with the distinction that in Figure 11 they are shown on a larger scale, whereby also the devices in connection with the track, such as signals, certain automatic stopping means, switch arrangements, bells, etc., are brought into connection with the circuits to make the invention completely comprehensible.

In the drawings the apparatus or mechanism constituting the essential features of the register controller is mounted upon a suitable indicator board 5 of electricity insulating material. In the drawings I have shown a plurality of individual section indicators mounted upon this board, which respectively correspond to individual sections or one or more particular points or locations in a single track railroad, and more particularly of the particular division of the railroad track represented by the register controller. The several indicators are shown in open and closed positions, as would occur in actual practice, upon a single track road having branches, junctions,

crossings, etc. The actual location of the trains, the position of the switches, signals, etc., and the occupied or unoccupied conditions of the connecting, crossing, branch or junction tracks will be indicated by the open or closed positions of the indicators, which are so mounted and designated that the movement of the trains or their position upon various parts of trackage may be ascertained at a glance.

I have shown the wiring connections for the operation of the register controller diagrammatically extending down from the individual controller units to the particular section or part of the track in the division of the line which such control unit is intended to represent. The wiring connections for operating and controlling the various remotely located devices or mechanisms which are operated and controlled by the register controller are also illustrated.

In the embodiment of the invention herein illustrated, each unit of the register controller includes an indicator 33, which is mounted for rocking movement upon the common supporting rod 34, though if desired, these indicators can be arranged upon individual supports. The movement of the indicators from a normal inoperative position to an effective or operative position is accomplished by means of a link 35 connecting each indicator to the upper end of a pivoted part 37. The lower end of this pivoted part is thereby attracted by an electromagnet 36 when same is energized and a spring 37 may be provided to positively return the parts to normal position upon the deenergization of the electromagnet. However, this spring may, if desired, be eliminated and the indicator 33 so mounted and arranged that it will drop by gravity to its normal position.

The individual indicators above referred to are effectively operated by the electromagnets 36, which are in electrical connection with remote circuit closing contact points located at any portion of the track that the peculiar conditions in the railway system may render advisable, such as at each section of a particular division of the track, or at each switch, crossing, junction, or other selected location, as diagrammatically indicated in the drawing. The several indicators 33 in the series are so arranged and connected to the parts of the trackage system that they will consecutively indicate the progress of a train travelling in one direction over the particular division of the railroad.

This refers particularly to a special register controller arranged for indicating the progress of trains on a particular line and consequently also controlling the trains on this line.

My system however can be used also for

controlling numerous trains travelling on a particular section of the railroad where many lines are crossing such as practically is the case in terminals or other frequented places, whereby a special register controller may be used and the arrangement of this register-controller will be so that no consecutive indicating of the progress of a single train is intended by the respective indicators 33 although it may be possible to trace the train's progress by the function of certain of the register-controller units.

It will be seen from Figure 1 that several of the electro-magnets 36 have more than one electric connection with the remote track-sections and also with such points which are located on junctions or on lines which cross the main-line which in this Figure 1 is drawn by a horizontal line. Such connections with points situated on crossing lines or junctions, etc., simply are made for the purpose of protection of all trains travelling on that particular net of railroad-lines and therefore serve not only for the protection of trains travelling on one particular line.

In Figure 1 the points of the railroad from which electric impulses are sent to the register-controller are indicated by arrows; there are arrows however which indicate only the direction of traffic on these lines, but they are easily distinguished from the other arrows in that they have no wiring connection with the register-controller; also the remotely located devices such as might be used for controlling or signalling the several trains on the railroad line are indicated by arrows, the scale of the drawing obviously being too small to show the devices in their real shape. These last mentioned arrows are put to places on which the remotely located devices are thought to be situated. These devices which might be of the character of an electric bell 100 or electric lamp 110, or of a semaphor 120 or of an electro-magnet 130 which latter might form part of an automatic train-control device, are in electric connection with the wires 73 or 74 or 75, and according to the drawing must have one side of the electric connections grounded.

The wiring connections with the electro-magnets 36 do not show the source of electricity needed for the energization of the electro-magnets 36; this source may be carried by the trains, or it may be located on the roadside and the contacts for closing the circuit or for opening it may be of a great variety but preferably should be such as mentioned already.

Assuming that one of the electromagnets 36 is energized, the individual indicator 33 will be moved from the normal position seen in Figure 2 to a vertical or upright position, and will establish an uncompleted electrical circuit by coming into contact with

an exposed plug 38 movable through the board 5, said plug being engaged by the upper end of the indicator. The indicator will also come into contact with two adjacent metal circuit closing parts 41, mounted on the board 5, the indicator having an intermediate widened portion 42, which bridges the space between said contact plates. Thus it will be apparent that the plug 38 is electrically connected in the circuit simultaneously with the contacts 41.

However, the circuit cannot be completely closed until two adjacent indicators 33 are operated in the manner just described. Thus it will be noted from reference to the upper portion of Figure 1 that each alternate plug 38 is electrically connected with a source of current indicated by the generator 39, while the remaining or intermediate plugs 38 have individual electrical connections for controlling separate circuits each controlling and operating one or more remotely located devices whose operation it is desired to control automatically by means of the apparatus the trains located in the particular track division.

It is obvious that the circuit of the generator 39, if sufficiently strong current is used, could be employed for directly operating the remotely located devices. In order, therefore, to complete the circuit and conduct the generator current across two adjacent plugs 38 the adjacent indicators 33 are electrically connected with each other in a common circuit through the means of the contact plates 41. It will thus be seen that only when the two adjacent indicators are in their upright or vertical positions upon the board 5, is an electrical circuit completed to operate the particular remotely located devices which are controlled by that circuit.

The path of the circuit would then be from the ground through generator 39 and one of the plugs 38 through an indicator 33, the part 41, then through the other indicator 33 engaged with said part 41 and out through a wire 70 or 71 or 72 connected to the other of the plugs 38 to the remote devices in electrical connection with this particular portion of the register controller, as indicated by the positions of the first two indicators 33 at the left in Figure 1, and then to the ground.

For purposes of illustration I have shown the remote signaling or indicating devices in Figure 1 of the drawings as consisting of an alarm bell 100, a signal lamp 110, a semaphore 120, and an electromagnet 130, which latter may be arranged to actuate suitable automatic stop means for the train. In the operating circuit for these devices the mercury well circuit closer 140 is arranged and operates to cut in a stronger electric current furnished by the generator 150 than can be supplied by the generator 39. This circuit closer may be of any approved type, as, for

instance those indicated by 151 and 152 but as herein shown with the circuit closer 140 includes an electrically actuated plunger 160 which operates to cause the mercury to 5 come into engagement with spaced contacts, whereby the generator 150 will be connected in the circuit.

As shown in Figure 2 of the drawings, an arm 43 may be associated with any one 10 or more of the controller units, said arm being pivotally mounted upon the board 5 at one of its ends, and adapted to drop downwardly by gravity and contact with the plug 38 at its free end. This arm may 15 be controlled by either electrical or mechanical means, and is released for movement to its operative position whenever a certain train is to be switched or some certain other device located at some particular 20 point along the track be operated, as shown in Figure 2. The part 43 may, however, be mounted for manual operation, if desired. The object in providing this pivoted arm 43 is to enable the immediate or future operation of a particular switch or device, or 25 a series of them.

The particular indicators 33 which are to contact with the arms 43 used for future operation of a certain switch, etc., are of the 30 type which will not indicate the progress of the trains, but simply will serve the purpose of preparing and making the closure of the circuit or circuits which are to operate the said particular switch or certain other 35 device through arm 43, etc. For obtaining the closure of this last mentioned circuit, the respective train after having automatically connected the arm 43 with a plug 38, being not directly connected with the generator 39, this at a moment when passing at 40 a particular location or when starting at a station, for instance, at a terminal, etc., and when reaching a certain location along the track may close one or several circuits for 45 operating the two indicators 33 simultaneously, or one shortly after another, so, however, that the electric current from generator 39 will pass through the arm 43, wire 43' to the remotely located devices 50 where it will be grounded. Through the pressure of the indicator 33 upon the part 43 and the plug 38 a good electric contact is created.

In railroad practice there are numerous 55 instances in which this scheme may be employed; there are also such situations in which one indicator 33 may be operated by one train while the adjacent indicator 33 is to be operated by another train, as, for 60 instance, such situated on an adjoining block.

In practice the part 43 and its operating 65 connections will be placed in juxtaposition to a particular unit of the register controller which controls the operation of a certain

switch or other device along the track, and if immediate operation is desired, this part 43 will be located above and arranged to make contact with one of the live plugs 38 which is in electrical connection with the generator 39. It is thus apparent that when this part engages the plug 38 the path of the current will be from the ground through the generator to the plug 38, then to the hinged part 43 and through the wire 43' to the special switch or other device to be immediately operated.

However, if future and not immediate operation of the switch or other device is desired, the hinged part 43 is mounted and 70 arranged to make electrical contact with one of the plugs 38 which is not connected to the generator 39. Consequently, the operation of the switch or device which is in electrical connection with this part 43 will be 75 delayed until the indicator 33 which when operated is contacting directly with the plug 38 on which then the hinged part 43 is brought into contact, is operated and is 80 pressing against the then lower end of 43 85 and consequently also (but indirectly) against said plug 38, and until the adjacent 90 unit of the register controller is also operated to place the live circuit plug 38 in the circuit. Of course the first just mentioned indicator 33 (register-controller unit) 95 may be operated right after the part 43 is operated by the same train. The path of the current will then be from the ground through the generator to a live contact plug 100 38 to the indicator 33, the electrical contact plate 41, the adjacent indicator member 33 and hence to the hinged part 43 and through the wire 43' to the switch or other device to be operated, and then to the 105 ground as mentioned already.

The part 43 is automatically moved to its operative position by the mechanism shown in Figure 2. Thus each train is provided with a projecting part 44, which may be 110 vertically adjusted to selectively engage any one of a series of pivoted arms 45. This arm is connected by means of the flexible element 46 to a hinged lever 50, which supports a plate 51 pivoted at one of its ends 115 upon the rear side of the board 5. A wire or other flexible member 52 connects the free end of the plate 51 to the arm 43 and this wire or flexible member 52 is electrically 120 insulated at 52' so that no electric current can pass to plate 51 and accessories thereof and therefore no short-circuit through 52 will happen if for instance the two respective adjacent indicators 33 are operated but 125 arm 43 not lowered and contacted with its plug 38. When the arm 45 is actuated, the lever 50 is moved upon its fulcrum, and in turn forces the plate 51 upwardly and backwardly to the position shown in dotted lines in Figure 2, thus permitting the part 43 to 130

drop by gravity downwardly upon the contact plug 38. This part 43 will remain in its operative position until the particular indicating member 33 is going to its normal inoperative position, whereby the hinged part 43 being released by this particular indicator 33 is forced upward to its inoperative position by the hinged plate 51 which is falling to its horizontal position. 5 It must be remembered that the hinged plate 51, being far heavier than the hinged part 43 (see top-view of Figure 3) has been pushed out to the position 85 indicated by dotted lines in Figure 2 and Figure 4; this 10 occurred at the moment the particular indicator 33 has been operated to active vertical position and thereby was pushing the free end of 43 and therewith the plug 38 against (and the latter partly through) the board 5, whereby, by means of the pin 53 which being united with the plug 38 the plate 51 has been pushed from the position 84 to the position 85 (see Figure 4). It will be noted from the drawings that the pulley 86 is so 15 positioned that the plate 51 will make a pull upon the flexible member 52 only when being in the position 85 but not when being in the position 84; therefore as soon as the particular indicator 33 is going to its released position as shown in full lines in Figure 2 the hinged part 43 will be pulled upward again to the position seen in full lines in Figure 2. This however, would not happen if plate 51 was still in the position 84. 20 At the moment the particular indicator 33 is going to its inoperative position the coiled spring 53' being partly surrounding, the pin 53 is pushing the plug 38 outwardly to the left (Figure 2) and therewith also the pin 53 in this direction, so that plate 51 would again be turned to the position 84 when pushed by the lever 50, since pin 53 would not hinder this except when the particular indicator 33 is operated to active 25 position. Plate 51 being of heavy metal will if dropping to its horizontal position push down lever 50 and thereby cause a pull upon the flexible member 46, whereby the particular hinged lever 45 will be automatically restored to its normal position should not other means like a spring, etc., which are not shown, do the function of restoring the lever 45 to normal position which is shown in Figure 2. 30 In Figure 2 and partly in Figure 5 the mechanisms for automatically operating a track-switch are shown, and comprise an electric motor 55 which is operated by the circuit which in turn is controlled by the part 43. If desired, however, this motor may be controlled by some one of the register controller units shown in Figure 1. When the motor 55 is operated, the endless link chain 56 is moved, said chain is then 35 turning the pulley 57 which pulls chain 58 which is suitably attached to 57 by its one end. This chain 58 operates thereby an eccentric plate 59 to which it is attached with its other end. Operatively connected with the eccentric plate 59 is the switch bar 91 70 which in turn is suitably connected with the switch tongue or tongues 54. At a certain position of the eccentric plate 59 the switch tongues will be so placed as to keep the side line open for the train and this will be obtained when the motor 55 is electrically operated, and at a certain other position of the eccentric plate 59 the side line will be closed by the switch. I have provided means for automatically resetting the switch tongues 75 to their former position so that for instance another train which had to travel in the direction of the arrow 92 would find the switch open for this direction. Also such automatic means are included which will shut off the electric current from the electric motor at the proper time. For this purpose a lug 60 is secured upon the endless chain 56 and is so placed as to automatically actuate a switch-element 61 and thus cut off the supply current for the motor 55, so that the operation of the latter ceases at a predetermined point in the travel of the link-chain 56 which is determined by the extent of movement of the switch-points 54 necessary 80 to move the same to their open or closed positions. 85

In Figures 9 and 10 I have shown the particular arrangement of the automatic means for connecting and disconnecting the circuit with the fields of the electric motor (55). 90 In these figures I have shown the conductor 43' (which is seen also in Figure 2), connected with the conducting part 61' of the switch-element. The switch-element 61 consists of two parts, namely said conducting part 61' and the outer arm 61 thereof which merely serves for the engagement with the lug 60. This arm 61 may be electrically insulated from the conducting part 61'. Approximately at the center the switch-element is pivoted as at 163; if then the motor is energized and revolves the pulley 164 in the direction of the arrow seen in Figure 2, the endless link chain 56 is also 100 moved so that the lug 60 which is fastened on same pushes the outer arm 61 of the switch-element to the position shown by dotted lines in Figure 9. At this position the conducting part 61' of the switch-element comes out of contact with the contact part 162 which is directly connected with the respective fields of the electric motor 55. 105 It is thus apparent that thereby the electric current is cut off from the electric motor 55. 110

115

120

125

130

60 and the outer arm 61 is the flexible member 165 which is so arranged and fastened on these parts that the lug 60 will pull the outer arm 61 to the left, the position shown in 5 full lines in Figures 2 and 9, when a pull in the direction to the left is exerted upon the chain 58, whereby the pulley 57 is getting turned in the direction which causes the link 10 chain 56 to move also in the direction which causes the lug 60 to pull back again the outer arm 61 and to thereby restore the conducting part 61' again upon the contact-part 162 of the motor 55.

15 The parts and causes which make a pull upon the chain 58 will be explained subsequently. In Figures 2, 9 and 10 it is seen that one side of the circuit which operates the motor 55, is grounded as at 166.

20 The automatic means for resetting the switch-tongues consist of a tripping means 63 which is rigidly united with a crossbar 64 which has its other end bowed and linked with a bar 65 which in turn is connected by its other end with the eccentric plate 59. The 25 connection of bar with the eccentric plate 59 is so selected that at the partly turning of the trip means 63 to one direction the eccentric plate will be moved to close the switch for the junction or siding and at the same 30 time will pull upon the chain 58 and therewith turn pulley 57 in the other direction as previously mentioned, so that the lug 60 puts the switch member 61 in a position which permits the closing of the circuit for the 35 operation of the electric motor 55. This circuit is controlled by the hinged part 43 and if the arrangement is made for future operation the circuit controlling parts would include some of the particular adjacent units 40 33 of the register-controller.

45 A certain pair of these units 33 without the cooperation of arm 43 might also control this circuit. It is understood that at the moment on which all wheels of the train 50 have passed at the switch-tongues, the circuit must be opened already which had energized one of the electro-magnets 36 through which the certain units of the register-controller have been operated which in 55 turn have closed the circuit for the operation of the electric motor 55; thus it will be seen that the electric motor 55 is not energized but the electric connections are made so that an energization of it will be obtained right away through the circuit closing position of the particular units of the register-controller. In case of an immediate operation 60 of the track-switch such as might be done by the simple contacting of the part 43 with a plug 38 being directly electrically connected with the generator 39 the particular indicator 33 usually cooperating with this plug is to be electrically operated when the train reaches a certain point along the track 65 which even might be the next signal, and

this particular indicator 33 must be released when another particular location along the track is reached by the train to thereby permit the resetting to pulled up position of the part 43 and by this the deenergization of the electric motor 55 and consequently permit also the automatic resetting of the track-switch. 70

Every train carries a suitable lug 67 shown in Figure 6 or other trip element at the rear of the last car or coach, which engages the part 63 located in the track, so that the switch points will be reset to their former position at the moment when all wheels of the train have passed at the switch tongues. 75 80

There is still a second trip device 63' which is so positioned that a train travelling in the direction of the arrow 93 will operate the switch tongues so as to place them in a position as seen in the drawing whereby a 85 train which has to travel in the direction of the arrow 92 will not be switched to the junction, this in the direction of the arrow 94.

90 Although said second trip device 63' does not directly form part of the invention and will serve only when the railroad-lines which are connected with the track-switch illustrated by Figure 5 are used for traffic in both directions, a short description of the actuating parts of this trip part 63' is made hereafter. There are several ways for causing the trip means 63' to make similar movements which the trip device 63 does. 95 The trip device 63' must be in vertical position (see Figure 7) when the trip device 63 is also in vertical position and must be in inclined or approximately horizontal position though in an opposite direction when the trip device 63 is also in such inclined 100 position. These positions determine also the 105 positions of the switch-points 54. In Figure 5 there is only a dotted line shown for merely indicating that there is a connection between 110 63' and 63. This connection, however, is more precisely shown in Figures 7 and 8 where one end of the chain 111 is fastened at 105 of the trip 63 while the other end of this chain 111 is connected to a point 106 being 115 located on a similar part on trip 63' and on the same side as the part 105 of the trip 63. The result is that when the trip means 63 makes a movement which tends to pull the chain 111, the trip-means 63' is thus forced to 120 make likewise a movement but to the reserve direction. For erecting again 63', another chain 112 is necessary which for accomplishing this, must have one end fastened at the point 107 of the trip 63' while the other end must be fastened on a similar point on the same side of the trip 63; this point is 125 designated by 108. A roller 115 may serve as support for both or only one of the chains. From the foregoing description it will be 130 seen that the trip 63' can actuate the trip

device 63 when a train strikes the erect trip 63', whereby also the track-switch is getting actuated as explained already and the electric switch means of the motor 55 are put 5 into such a position that another actuation of the track-switch can take place. It is of course, understood that the motor 55 operates only in one direction and until it is stopped by the electric switch 61 when shifted by the 10 part 60. At the automatic resetting of the track-switch the movement of the link belt 56 is reversed, so that the rotation of the armature of the motor 55 will likewise be reversed and again disposed in position for 15 the operation of the switch points when the motor field is subsequently energized; and the electric switch 61 will be put to closed position by the lug 60 at a certain moment in the travel of the latter.

Having described the invention to some extent so that many details are understood, I show in Figure 11 the invention as it might be employed in practice, and to this end the railroad-net of Figure 1 is shown on a much 20 larger scale, and the remote devices in connection therewith which in Figure 1 are only indicated by arrows are also shown. As the register controller shown in Figure 11 is of the same construction as the register controller of Figure 1, except that some more 25 indicators 33 and the parts connected therewith are shown, the description of Figure 11 will deal chiefly with the circuits. The several tracks (railroad lines) are designated by c^1 , c^2 , c^3 , c^4 , c^5 , c^6 , c^7 , c^8 , etc. The track c^1 is straight for a certain distance and is divided into blocks by the insulations d^1 , d^2 . On the block A of the line c^1 a train is situated which is represented by a pair of 30 wheels and their common axle. There is a battery 170 carried by said train and conductors 171', 172' are in electrical connection with a pair of wheels 171; 172—say, the first ones of the train. To the one rail 173 is connected the wire 174, which again is connected to the winding of the electro-magnet 36 of the second indicator on the register controller. This register controller may be located in the station 175, or in some 35 other suitable place. To the other end of the winding of this electro-magnet 36 the wire 176 is connected and grounded at 177. The rail 173' is grounded at 178. All those trains which travel on the line c^1 and also those trains which travel on the lines c^5 and c^7 are assumed to belong to one railroad system where the signalling system differs from that which is used on the lines c^2 , c^4 , c^5 , and c^6 . These latter lines may form part of 40 another railroad system. The trains which travel on the line c^1 have insulations on each wheel axle so as to electrically insulate each right wheel of the train from each left wheel of the train. It is thus obvious that the circuit repeated by the following numerals:

170, 171', 171, 173, 174, 36, 176, 177, 178, 173', 172, 172', 170, will not be short-circuited by the other train-wheels. The two rails 173, 173' must be electrically separated one from the other. The thus energized electro-magnet 36 of the second indicator unit 70 attracts the part 37 and causes thereby the indicator 33, its part 42 respectively to contact with the next situated contact parts 41, as has been described in connection with Figure 1. 75 To the rail 173 of block B a wire 174' is connected and also electrically connected to the electro-magnet 36 of the second indicator unit and the other rail 173' of block B is grounded in a similar way as the rail 173' of 80 block A. It is thus shown that the electro-magnet 36 of the second indicator unit will be energized also when the train enters the block B and travels along same. If there was not the crossing line c^2 which intersects 85 with the line c^1 right through block C thereof, then the wire 174' could be connected to the electro-magnet 36 of the third indicator unit, and this may follow in a consecutive order. It is thus apparent that the train's 90 progress could be read clearly from the consecutive operation of one indicator 33 after the operation of the next previous one, assuming that there is only a line without intersecting lines, branches, junctions, etc. In 95 order, however, to fully protect the train, several blocks may be electrically connected with the same electro-magnet 36 of the register controller. From the plan of Figure 11 it is shown that there is also a train situated on the line c^2 , and that this train is approaching the crossing point of the line c^1 . On line c^2 which may belong to another railroad system a different signalling system 100 is employed. It is not part of this invention to describe the mechanism or function of the signals which are employed on the line c^2 , but it may be mentioned that there are track-circuits employed with track-batteries 180 and the signals 181 of this line 110 go to stop-position when a train enters the respective block and short-circuits the track circuit, such as is done by the train 182, represented by a pair of wheels and the axle thereof. In the case of the line c^2 the electric connection with the register controller must be made so that no track-rails are employed in the circuit which energizes the 115 respective electro-magnet 36 of the register controller, but contacts are used which are operated by the train or by the signals. When the circuit is closed by contacts operated by the train a shorter energization takes place usually than when the circuit is closed by contacts operated by a signal, because in the latter case the signal will be set to stop-position as long as the train or a pair of wheels is situated on the respective block. 120

The form of register controller shown in this invention requires, however, that the 130

indicator 33 remains in operated position as long as the train or trains which caused the operation of the particular indicator 33 is situated on the particular block or section of the railroad-line which is represented by this particular indicator 33. It would be different if only a short operation of an indicator 33 would be sufficient for merely indicating the progress of the train, as it may be used on a single line without crossings, branches, junctions, etc., whereby simply a bell 100 may be rung for a short time or an electric lamp lighted.

Referring to the electric connections of the line c^2 (Fig. 11) with the register controller the signal 181 is provided with two contacts 183, 184. To the contact 184 is connected the wire 185, which, again, is connected to the winding of the electro-magnet 36 of the third indicator unit of the register controller. The other end of this winding is grounded at 177'. The contact 183 is connected by a wire 186 which is in connection with a battery 187 whose other side is grounded at 188. The contacts 183, 184 will be contacted only when the signal arm 181 shows the stop-position, and thereby the circuit is closed in which said electro-magnet 36 of the third indicator 33 is included and the result is the moving of this indicator 33 to operative position and the holding of same in this position as long as the signal 181 is set to stop-position.

The two neighboring indicators 33 close the circuit which in Fig. 11 is traced as follows: generator 39, wire 39' plug 38, not shown because contacted by the second indicator 33, contact plate 41 between the second and third indicator 33, the third indicator 33, plug 38 contacted by this third indicator, wire 70, relay 189 (which in Fig. 1 is shown in a different form), and ground 190. The armature 191 will be attracted and contacts with the contact 192, whereby a circuit is closed with which special stop signals are operated and set to stop-position, or trip devices may be operated to move into the path of a lever on the train, and this lever may be so arranged and in connection with the air-brake system or other brake systems that its operation by said trip device beside the track will cause the stopping of the trains. Or it may be a so-called ramp system which is also used for stopping the train automatically, and in this case the electric impulse may be sent to the ramp, or it may be a relay which interrupts the electric current that normally may be conducted to said ramp.

These automatic train stopping systems do not form part of this invention, and as they are sufficiently known by those skilled in the art, it seems to be unnecessary to go further into details thereof.

It is necessary that those trip-devices or

stop-signals or ramps, etc., be operated which will halt the train before it reaches the crossing point of the lines c^1 , c^2 , and therefore I prefer to connect the circuit also to such stopping devices or signals which are situated more than one block away from the crossing point of these two lines. There is, for instance, one 193 in block A and in block B in form of a ramp, while on the line c^2 tripping devices are employed which are indicated by 144, 195.

By arranging these devices in such manner it is possible to bring also such trains to a stop which would be advanced very near to the crossing point of the lines c^1 , c^2 , and such trains will be halted also which might be following such trains that it advanced already very close to said crossing points. Arrangements can be made whereby at least one train should have the right of way, that is, the right to pass at the crossing point while the other train on the crossing line has to wait until the first train has passed completely at the crossing point. According to the disclosure of the system on the line c^2 it is evident that the train 182 when entering the next following block would cause another circuit to be closed while the circuit with the battery 187 will still be closed as long as there is on this block a pair of wheels of the train 182. Instead of connecting the contact 184 of the signal 181' to a wire that is also connected to the electro-magnet 36 of another indicator unit, I electrically connect this contact with the same wire 185 with which the contact 184 of the signal 181 is connected, and instead of using a special battery which when grounded would cause a short circuit with the ground and electric connections of the battery 187,

I prefer to connect the contact 183 of the signal 181' with the wire 186 by means of the wire 186'. When the train 182 operates the signal 181' the circuit will be closed which is traced by the following numerals which indicate the electric connections: 187, 186, 186', 183, and 184 (of the signal 181'), 184', 185, 36 (of the third indicator 33), 177', 188, 187. The signal 181' is shown in proceed-position because no train is in the respective block and because no electric connection is made between it and the register controller. But there is another signal shown which bears the reference number 195^a, and as this signal is in electric connection with the conductor 73 and consequently with the generator 150 it is evident that this signal will be in stop-position as well as the next trip device 195, which is also included in the circuit in which the generator 150 is included.

This circuit, which may include all the stopping devices of the sections involved of the lines c^1 , c^2 , c^3 , c^4 , as far as shown in Fig. 11, and which may also include certain signals or bells for sounding

alarms, or electric lights for signalling purposes, is traced as follows: battery 150 which is grounded on one side at 151', wire 151^a, armature 191, wire 73; to the wire 73 are connected the wires 205, 206, 207, 208, 209, 210, 210^a, 211, and 213. These wires 205 to 213 inclusive are connected to the respective devices beside the track, such as ramps 193, to which the wire 206 is connected, or signals to which the wires 205, 207, 208, 210^a are connected or stopping devices like those indicated by 194, 195, 196, 214, to which the wires 209, 210, 211, 213 respectively are connected. Some of the wires 205 to 213 may have resistances according to the requirement in the construction of the devices having connection with these wires. These devices are not shown in detail, but it may suffice to say that an electro-magnet may be used in connection therewith, or a relay and it is the energization of this electro-magnet or relay which will cause the effective actuation of such signalling or stopping device, which practically is the case in nearly all devices of that kind which are known and which are to be operated from a remote point. The construction of such signalling and stopping means as well as the parts on the train which correspond with these means, especially the stopping devices, are not shown nor described because they do not form part of this invention. It suffices to say that there are numerous systems, and among them those which make permissible control of the train, that is, let the train advance over conflicting routes with a low, that is, safe speed. The windings of said electro-magnets (not shown) which serve in connection with the devices beside the track, such as the signals and the stopping devices 194, 195, 196, 214, or ramps 193 may be connected at their other end by another wire (not shown) which, again, will be grounded so that individual circuits are created thereby because the generator 150 is also grounded at 151'. In order, however, to avoid short-circuits or to avoid a condition where some devices receive a strong impulse because they may be nearer to the generator 150, the connecting wires to the devices which are nearest to the generator should receive sufficient strong resistances, while the more remote ones will not have any resistances; or it may be that the circuit arrangements are made in a manner such that all the involved electro-magnets which might be indicated by 130, as shown in Fig. 1, shall be included in one single circuit, whereby the electro-magnet 130, being the remotest from the generator will be grounded. It may be mentioned also that the use of induction electricity will serve for operating the said devices beside the track. In such case the wire 73 would serve as the power-line while the trans-

formers would have to be installed at each of said devices beside the track and electrically connected with said electro-magnet 130 which serves for the effective operation of the respective device.

There is a junction *c*⁸ which is also in electrical connection with the register controller. The signal 181" on this junction has also two contacts 183, 184, and a battery 187 and the ground 188 are in electric connection with the contact 183, while the contact 184 is in electrical connection with the electro-magnet 36 of the third indicator unit. When this circuit is closed by the contacts 183, 184 and a train is situated on block A or B of the line *c*¹, also the stopping device 196 will be operated to go to stopping position.

The line *c*² may be a line for traffic in both directions. In this case it will be necessary that such trains which are situated above the line *c*¹ and which travel in a southerly direction (that is in inverse direction of the train 182) must first be protected against side collision with a train that comes in the direction of the arrow on line *c*¹ or from the inverse direction, and secondly must be protected against a frontal collision with a train that travels in a northerly direction on line *c*², or that may come from the junction *c*⁸ and enter upon the line *c*². Therefore the contacts 183, 184 at the signal 197 are in electrical connection with the electro-magnet 36 of the first and fourth indicator 33. According to Fig. 11 on this part of the line *c*² there is no train situated and therefore the electro-magnets 36 of the first and fourth indicators 33 are not energized, and consequently these indicators 33 are not operated.

Assuming, however, that a train should operate the signal 197 and a train should be on block A or B of the line *c*¹, and also the train 182 should approach the crossing point of the two lines *c*¹ and *c*², as shown in the drawing; then the four first shown indicators of the register controller would be operated by their electro-magnets 36 and a special signal 198 would be operated to go to "halt" position. This southerly going train may then enter upon the siding 200 and remain there until the train 182 has passed, so that the line *c*² will be free for this southerly-going train. The train on the line *c*¹ when entering the block C closes a circuit in which the electro-magnet 36 of the third indicator is included because the wire 201 is in connection with the rail 173 of block C and the electro-magnet 36 of the third indicator 33 which, like all other similarly arranged electro-magnets 36, is grounded. The other rail 173' of block C is also grounded, and therefore an electric circuit is created which is similar to that which has been traced in connection with blocks A and B of the line *c*¹. By entering

upon block C of the line c^1 the eastward-going train would encounter danger of a collision if a train should approach on the line c^3 . The train on this line, however, 5 will be stopped before entering upon the line c^1 on which it would travel in a westerly direction. As the system of the line c^3 is like that explained in connection with line c^1 , it is evident that a train entering the block 10 L or M of this line will close circuits in which the electro-magnet 36 of the fourth indicator 33 is included. This indicator will then go to operative position when the train is situated on block L and also when 15 the train is on block M. The third indicator caused to be in operated position by the train on block C of the line c^1 will then complete the electric connection which closes the circuit in which the relay 189 is included. This circuit is as follows: generator 39, wire 39^a, wire 39'', plug 38, the fourth indicator 33, contact plate 41 on the left, the third indicator 33, plug 38 thereof, wire 70, relay 189 and ground 190. It is shown 20 herewith that at the same time the lines c^1 , c^2 , c^3 , as well as the line c^4 are controlled by these four or five indicators 33. The train which comes from the line c^3 and is to continue its travel on the line c^1 in a westerly 25 direction will be protected from a front collision with the train on the line c^1 going in an easterly direction and will also be protected from a side collision with a train on the line c^2 going either in a southerly or 30 northerly direction. The train on the line c^3 will be signalled as to the traffic condition, that is, the presence of trains on line c^1 or c^2 or c^4 , and will be compelled to stop until there is no train situated on the sections of the lines c^1 , c^2 , and c^4 which in any 35 probability might collide with it when advancing. The devices 214, 215 may be signal devices on line c^3 and they may be brought into connection with stopping devices such as trips, etc., which are well known in the art and will enforce an automatic stop of the train should the engineer attempt to advance, despite the signal set 40 against the advancing of his train. The 45 electric connections which operate these stopping devices are also in electric connection with the wire 73, and therewith with the generator 150.

If no train should be situated on block C of 55 the line c^1 and on the sections of line c^2 shown in Fig. 11, and on the shown section of the line c^4 , the fourth indicator 33 would not have a neighboring indicator that is 60 operated for completing the circuit with the generator 39 except when a train is situated in the block D or E; then the fifth shown indicator 33 will be operated and will complete a circuit with the likewise operated fourth indicator 33, whereby the signals 214, 65 215 on the line c^3 are operated and those in

the blocks D and E of line c^1 . The circuit which serves for this purpose will be closed by the relay 151 which is constructed similarly to the relay 189, but connected by the wire 71. The circuit that will be closed by 70 the grounded relay 151 is as follows: generator 150, wire 218, armature 219, contact 220, wire 74, the respective electro-magnets or relays or even electric motors that may be employed in connection with the devices employed for controlling the trains 75 automatically on the line c^3 and on the blocks D and E of the line c^1 . Also in the case of the circuit in which the wire 74 is employed the connections may be made as 80 to suitability and in a manner as previously mentioned in connection with the circuit in which the wire 73 is included. On the drawing, Fig. 11, there is no train shown on line c^3 , and therefore no energization of the 85 electro-magnet 36 of the fourth shown indicator 33 takes place. The sixth indicator 33, however, is operated and a contact-part 43 is in connection with the plug 38 of this 90 sixth indicator, and this contact-part 43 as 95 shown is arranged for immediate operation of the switch in the block E of the line c^1 . A train that was travelling in a westerly direction on the line c^1 by passing at the station 175 has caused the part 43 to drop upon the plug 38, and at this moment the motor 55 in the chest 55' (see also Figs. 2, 5, 9 and 10) has become energized and operated the switch tongues in the manner already described. The circuit which energized this 100 electric motor 55 is as follows: generator 39, wire 39^a, connecting wire with the plug 38 of the sixth indicator 33, this plug 38, the contact-part 43, the wire 43', the electric motor 55, the ground 166, the ground 223 and the generator 39. The train, however, which 105 caused the contacting of the contact-part 43 with the sixth plug 38 had entered upon the block E in the meantime, and the switch is 110 then so positioned that the train can enter upon the line c^3 . At the moment in which this train was entering upon the block E the sixth indicator 33 became operated by the 115 electro-magnet 36 of this unit, because electric connection with this electro-magnet 36 is established by the battery (not shown) carried by the train, the first wheels of the train and conductors to this battery, the rails 173, 173' of which the latter is grounded and the former connected by the wire 225, 120 which, again, is in electrical connection with the sixth electro-magnet 36. As soon as the train has entered upon the line c^3 with the first pair of wheels the said sixth electro-magnet 36 will be de-energized and the sixth 125 indicator 33 will move again to its non-active position. At this moment also the contact-part or arm 43 will be pulled up again by the rope 52, which will be pulled by the falling plate 51, illustrated in Figs. 2, 3 130

and 4. The train when completely entered upon the branch-line c^9 will push the device 63 (see Figs. 5 and 6) and will automatically restore therewith the switch tongues 5 to their former position so that a train that might follow in block F and which had to continue its westward travel on the line c^1 would not be switched to the branch-line c^9 . In block F of the line c^1 as well as on the line c^4 there is no train situated, therefore the two neighboring indicators 33 are not operated. If, however, trains should be situated on these sections of the railroad, the same scheme would be employed which 15 has been explained at large in connection with the lines c^1 , c^2 , c^3 , c^8 , and therefore it would mean only a repetition of what has been said in connection with these lines and their relationship with the register controller. It will suffice to mention only that 20 the sixth indicator 33 will be operated when a train enters upon the block E of the line c^1 , and that the seventh indicator 33 will be operated when a train is situated on the block F of that line, whereby the wire 240 is employed, and also when a train is situated 25 on the section of line c^4 shown in the drawing, whereby the wire 241 is employed. This last mentioned train, however, will cause 30 also the operation of the eighth indicator in a circuit in which the wire 242 is employed. When the sixth and seventh indicators 33 are simultaneously operated the circuit is completed in which the generator 39 and the 35 wire 72 is included. This closed circuit causes the energization of the relay 152 which thereby closes another circuit in which the generator 150, the wire 218, the wire 244, the armature 245, the contact 246, the wire 75 and the several electric devices 40 as, for instance, electro-magnets, electric lights, bells, electric motors, etc., may be included, which electric devices may be employed in connection with the signalling devices on the points 247, 248, and also 45 249, or the electro-magnets or electric motors with the stopping devices 250, 251. The electric connection with these devices is made so that the wire 75 is connected to the electro-magnet of the device designated by 249, which is supposed to be a signal, and to the other end of the winding of this electro-magnet is connected the wire 75', then follows the motor or electro-magnet of the device 251, whereby the wire 75'' will be similarly connected as was explained in connection with the wire 75' and the electro-magnet of the signal 249. In the same order 50 of connection in the circuit follow then the electric devices in connection with the device 250, 248, 247, in which also lights may be included, or bells. It is shown that the circuit is grounded at 251', whereby the circuit 55 is closed through the ground 151', and the generator 150 when the armature 245

contacts with the contact 246, and as all these mentioned electric devices are included in this circuit it is evident that they will operate the devices 247, 248, 249 and 250 to go to stop-position.

Compared with Fig. 1 it is shown that in Fig. 11 a greater number of contact points, that is, railroad blocks are chosen for sending electric impulses to the register controller; the railroad net shown in Fig. 1 75 shows simply a general layout, while in Fig. 11 the circuits are shown in detail.

For illustrating how a future operation will be made of a switch of a similar construction to that situated in block E of line c^1 , the following scheme is described. Assuming that a train 229 is starting in block G of the line c^1 , that is at the station 175, and this train is to enter upon the line c^7 to continue its travel thereon. For setting the 80 switch tongues at the right moment, that is, not sooner than is needed, so that other trains that have to travel on the line c^1 in a westerly direction will not be switched to the line c^7 , the train in block G had operated in the manner described previously, the respective arm or lever 45 (see Fig. 2) which again causes the arm 43 above the thirteenth indicator to contact with the plug 38 of this unit. However, there will not be a closure 85 of a circuit by this action because the plug 38 is not in electrical connection with the generator 39 except when the thirteenth and twelfth or thirteenth and fourteenth indicators 33 are simultaneously operated. On its 90 travel, the train 229 will operate the eighth and ninth and then, as the next ones the twelfth and thirteenth indicators by means of the respective electro-magnets that will be energized one after the other. The twelfth 95 and thirteenth electro-magnets 36 are then energized simultaneously because the twelfth will be energized by the circuit in which the conductor 230 is included which is connected to the rail 173 of block K. The thirteenth 100 indicator 33, however, is not in electrical connection with the track-rails because any train other than that indicated by 229 that might travel thereon when the arm 43 is set upon the respective plug 38 would cause 105 the respective plate 50 to go to the position 110 illustrated in Figure 4, whereby the arm 43 would be pulled up when the indicator 33 would go again to its non-active position in which event the plate 51 will go to 115 its horizontal position, thereby pulling up the arm 43. For avoiding this inconvenience a switch device is employed which is to be operated by the train 229 by means of a lug 67 (see Figure 6) or similar part 120 that may project from one of the train units. The wire 269 which is connected to this switch-device is also connected to a battery 271, and another wire 269' is connected to 125 the other side of the battery 271 and to the 130

electro-magnet 36 of the thirteenth indicator. Said switch-device is grounded at 269^a and when the circuit will be closed in which the battery 271, the conductors 269, 269^a, the electro-magnet 36 of the thirteenth indicator is included, this indicator will be operated and will press upon the arm 43 and consequently also upon the plug 38 as long as the circuit is closed.

- 10 The train 229 which is then situated in block K will find the switch in a position that will let the train enter upon the stretch *c⁷*. The situation, however, is such that the train is to go either backward or another 15 engine is to be coupled to the rear of the train, which then would be the second unit thereof, and the former engine would be separated from the train. This is merely illustrative, and on numerous other track 20 arrangements it may be used where a switch or other device as, for instance, a signal or trip, etc., is employed whose future operation is performed by the register controller in cooperation with a train travelling on a 25 certain line. As soon as the train 229 has passed upon the line *c⁷* the twelfth and thirteenth indicators will go to or are already in inactive position, as has been explained in connection with the others. The 30 arm 43 above the thirteenth indicator will then be pulled up in the manner set forth, and the twelfth or even the thirteenth indicator when operated by some train that did not operate also the arm 43, will simply 35 cause some signal or control device, for instance, a stop trip, etc., to go to "stop" position. It may be made so, however, that 40 these indicators (the twelfth and thirteenth) will not close a circuit when operated simultaneously except when the arm 43 is lowered, as has been explained, or that the thirteenth alone would be without such electric connection except with the twelfth and fourteenth indicator and the arm 43. Referring 45 to the line *c⁴*, *c⁵*, *c⁶*, it is scarcely necessary to trace the circuits that are employed for energizing the electro-magnets 36 of the corresponding indicators 33, since the crossing line *c²* gives a full example, the lines 50 *c⁵* and *c⁶* being crossing lines. As regards the line *c⁴* there will be a similar arrangement as shown on the line *c⁸*.
- According to the area and the complexity 55 of the railroad-net that is to be controlled by the register controller a greater or smaller number of indicators 33 are necessary. The number of indicators on the register controller of Figure 11 might be reduced so as to control only the part of the line *c¹* from 60 block A to block E, and the crossing line *c²* together with the branch-line *c⁸*, while for the control of other following blocks of the line *c¹* and involved branch lines or crossing lines a second register controller of the 65 same construction may be employed, and

others for still further advanced blocks or other sections of the railroad-net, thus making it possible to shorten the wires that would be needed for the circuits, when these other register controllers are to be positioned in stations that are nearer to these railroad sections.

In Figures 1 and 11 a railroad-net is shown which is of a complicated character, it is therefore not practical to use this register controller for tracing the train's progress, as, for instance, that on line *c¹*, but a special register controller may be employed on which one indicator 33 will represent only one block and each following indicator 75 its respective other block. It is thus apparent that the progress of the train can be seen from the indicators 33 when they are operated one after another in a consecutive 80 order. A following train will then operate the indicators that shortly before had been operated by the first train. Should then the rear train go faster than the first train then soon two neighboring indicators 33 will be 85 operated, and the result will be the stopping 90 of the rear train and signalling the first. There may be sidings provided on the railroad line whereby in case the rear train should have the right of way over the first 95 train the first train could enter a siding and remain there until the rear train shall have passed. In this event an automatic switch 100 will be necessary, which, however, will be operated by the motor 55, whose energization was obtained by a circuit that was closed by two simultaneously operated 105 neighboring indicators 33.

It is obvious that such register controllers 105 may be constructed and circuits brought into connection therewith whereby the indicators 33 will serve only for indicating the progress of the train or trains, and for this reason it may suffice that only a short electric impulse is made in the respective block 110 of the track for operating the indicator only a short time, sufficiently long, however, to show in which block of the line the train is situated.

Especially in connection with the system 115 employed on line *c¹* the length of the trains is supposed not to exceed about one-half the length of a block of this line in order to avoid rear-end collisions. This rule may apply also to other lines and in connection 120 with a register controller which represents only a single line without branches, junctions and crossings.

From the foregoing description, considered 125 in connection with the accompanying drawings, it is believed that the construction and manner of operation of the invention will be clearly understood. It will be seen that the apparatus is entirely automatic in its operation, and does not depend 130 upon manual assistance of any character for

its efficient operation. The several cooperating parts of the mechanism are of relatively simple form, and can be manufactured and installed for use in connection with various railway operating systems at nominal initial cost. It is also apparent that in view of the simplicity of the mechanism, the same is not liable to get out of order, and will, therefore, require only infrequent inspection and repair.

While I have herein shown and described the preferred form, construction and relative arrangement of the various parts, it is, nevertheless, to be understood that the same is susceptible of considerable modification, and I accordingly reserve the privilege of adopting all such modifications and changes as may be fairly embodied within the spirit and scope of the invention.

20 I claim:

1. In a register controller for railroads, a plurality of controlling units arranged thereon, electrical means for operating said controlling units, operatively connected to different parts of the railroad, a remotely located device and a circuit therefor, adjacent controlling units being located in said circuit and independently normally rendering the circuit inoperative to actuate said device.

2. In a register controller for trains, indicating members in multiple arranged thereon in consecutive order and never touching on another, each indicating member having an electro-magnet and each indicating member being adapted to be operated by its individual electro-magnet independently from the other, a circuit, this circuit being completed only when the two indicating members included in this circuit are simultaneously operated by their electro-magnets, remotely located devices arranged for operation by said circuit.

3. In a register controller for railroads, a railroad-line divided into sections, a plurality of controlling and indicating units arranged on the register controller, each unit having relatively stationary and movable parts, an electro-magnet for some movable part of each unit and individual energizing circuits for said magnets each being electrically in connection with its respective section of the railroad-line, said controlling

and indicating units and their respective circuits being so arranged as to indicate the position and consequently the progress of the train along said railroad line, a circuit, said circuit being closed and operating remotely located signaling and controlling devices in connection with the railroad-line when two of said controlling and indicating units being adjacent are simultaneously operated by their respective electro-magnets.

4. In a register controller for railroads, a plurality of controlling units operatively arranged on a board of insulating material, electrical means for operating said controlling units operatively connected to different parts of the railroad, remotely located devices and individual circuits for said devices, adjacent controlling units located in one of said circuits and independently normally rendering the circuit inoperative to actuate said devices, said adjacent controlling units being independently operated by trains located at different points upon the track and additional means on the register controller for effecting the immediate operation of the remotely located device and such means for effecting the delayed operation of the remotely located device.

5. In a register controller for railroads, a plurality of controlling units each having a pivoted indicator member, a stationary part arranged to be contacted by two operated adjacent indicator members, an electro-magnet for each indicator member, individual energizing circuits, for said magnets connected to different portions of the railroad, a source of current and circuit connections including parts of the second, fourth, sixth, eighth, tenth, twelfth of said units and said source of current, remotely located devices and circuit connections between them and a part of the remaining first unit, another circuit connection with the fifth, another one with the seventh, another one with the ninth, another one with the eleventh, the circuit for the operation of the remotely located devices being closed when two or more adjacent indicator members then located in this circuit are simultaneously contacting with their respective stationary part.

HEINRICH KARL.
